MAX HOPP, OF NEW YORK, N. Y., ASSIGNOR OF ONE-HALF TO MAX LEVINE, OF NEW YORK, N. Y.

CARBON ATTACHED PRINTED FORM

Application filed October 5, 1931. Serial No. 566,931.

This invention relates to copying or transfer sets having carbon sheets included therein to form unitary devices.

One object of the invention is to provide a device of the character described having original and copy sheets together with carbon sheets detachably interconnected in an improved manner.

Another object is the provision of an improved unit including a top face element and one or more associated elements positioned thereunder with one or more interposed members for transferring or facilitating the transfer of an indicia from the top to a lower element, and wherein the members for effecting the transfer are readily removable from the unit, or all parts of the latter separable in any desired order and preferably without mutilation of the elements.

Other objects of the invention reside in the provision of an improved means for detachably connecting a carbon sheet or the like; an improved construction of a carbon sheet, or the like; an improved unit having relatively few and simple parts, and which is inexpensive to manufacture, and convenient, expeditious, reliable and efficient to a high degree in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference characters throughout the several views.

In the drawings:

Figure 1 is a plan view of a device embodying the invention.

Fig. 2 is a sectional view taken on line 2—2 of Fig. 1.

Fig. 3 is a side edge view of the same.

Fig. 4 is a plan view of the invention showing the carbon sheets in course of being removed.

Generally described, the invention provides an improved copying unit which can be

quickly, easily handled and which may include an original and one or more copy sheets together with carbon or equivalent means for bringing about a suitable transfer of indicia from the original to the copy sheets. This unit may be embodied in widely varying forms and constructions and for many different purposes. While the original and copy sheets may be in the nature of printed forms, they may also be otherwise prepared, or may even be blank. The unit may be inserted into a typewriter or other machine, but the indicia may also be formed or impressed by hand. While the material of which the unit consists may be paper, other materials may also be employed according to the required purposes and uses of the invention. In the preferred use of the device, it is contemplated that after the unit has been withdrawn from the typewriter, the carbon sheets shall be removed all together and in a single operation. The original and copy sheets may be coincidentally separated, or subsequently detached from one another, in any suitable manner but preferably without mutilation of said sheets, or requiring any act other than the separation itself. Thus the original and copy sheets may be detachably interconnected along one portion or edge, but without connection with the carbon sheets, and there being a separate line of detachable interconnection between the carbon sheets and any or all of the other sheets. These lines of interconnection may be of substantially equal strength but preferably the latter is weaker than the former. The lines of connection may be in any suitable relation or proximity but are preferably suitably spaced or remote from each other. The line of connection between the original and copy sheets may include any desired fastenings such as clips, adhesive, or the like, while the line of connection for the carbon sheets may include similar detachable fastenings, but preferably small spaced points of connection which may include adhesive, or perforations forming connecting burr like portions, or otherwise creating a thin easily detachable line of engagement. Where a carbon sheet is used and attached as above mentioned, it is desirable that the connected por-

tion of the carbon sheet shall be suitably treated or caused to be free of carbon and oleaginous material which may tend to hinder the connection, and if perforations be used, 5 might cause slipping and accidental release of the engaging burr like portions.

The advantages of the invention as here outlined are best realized when all of its features and instrumentalities are combined 10 in one and the same structure, but, useful devices may be produced embodying less than the whole.

It will be obvious to those skilled in the art to which this invention appertains, that 15 the same may be incorporated in several different constructions. The accompanying drawings, therefore, are submitted merely as showing the preferred exemplification of the invention.

20 Referring in detail to the drawings, 10 denotes a device embodying the invention. The same may include an original sheet 11 and one or more copy sheets 12 of any desired relative form or size, and preferably coextensive 25 as shown. These sheets 11 and 12 may have similar ruled lines thereon if desired. Interposed between said sheets, there may be provided any transfer means such as one or more carbon sheets 13, which may for distinction, be shown slightly thicker than the other sheets. These carbon sheets may terminate 30 at 14 in spaced relation to the upper edge 15 of the original and copy sheets, and may have any other or all its remaining edges in coincidence with those of the sheets 11, 12. For instance all side edges of the sheets 11, 12, 35 13 may coincide at 16, and at the bottom at 17, except that a suitable cutout may be provided in the original and copy sheets, at some 40 practical point, as at 18, at which the carbon sheets may project as at 19 to afford a finger grip.

At the top 15 of the unit, there may be provided a detachable binding or fastening 20, 45 which may interconnect the original and copy sheets, but without engaging the carbon sheets that are spaced therefrom. The fastening 20 may preferably be of a type such as is commonly used for connecting together 50 the sheets of a pad of paper, and consisting of a fabric of loose mesh with a filling of adhesive material that engages the sheets of paper.

Spaced from the fastening 20, and preferably formed along an edge of the unit, as, for 55 instance, along the bottom edge 17, is a co-operating detachable fastening 21 which serves particularly to connect the carbon sheets 13 in place. This fastening 21 may 60 preferably include a line of perforations pressed through the sheets of the unit so that the burr like projections formed in perforating will interconnect the sheets. The carbon sheets may have an edge portion 22 free of 65 carbon or oleaginous matter, the perforations

being formed through this portion. Hence the perforated connection cannot become accidentally loosened as by a lubricant action. Any number of sheets may be held together in this manner.

70 It will now be seen that the invention includes coacting detachable fasteners, one of which holds all the sheets together, and the other holds only the original and copy sheets together. Due to the spacing of the fasteners, 75 all the sheets are reliably separably held in a unit. Furthermore, the fastening 21 may be considerably weaker than the fastening 20. However, the sheets 11, 12 which closely embrace the carbon sheets therebetween, aid the fastening 21 for removably securing the carbon sheets, and the fastening 20 in proximity to the carbon sheets also affords an aid. Hence the entire device may be readily handled and manipulated as a unit.

80 This invention may be inexpensively constructed, as by first forming the sheets 11, 12 and interconnecting the same at 20. Then the carbon sheets 13 may be inserted, and the line of perforations 21 formed, completing 85 the unit.

90 In operation, the device may be inserted into a typewriter, and withdrawn therefrom in a unitary form. Then the portion 19 of the carbon sheets may be grasped, and in a single movement, all the carbon sheets may be withdrawn, the perforated line of connection readily giving way under the pull, so as to leave only the sheets 11 and 12 together. The latter may then be detached from each 95 other. The carbon sheets may be discarded. The original and copy sheets will be free of any mutilation, especially at the headings thereof, and the line of small perforations being remote from the heading will be insignificant and will not detract from the appearance of the sheets. No removal or severance 100 of any part of the sheets is necessary to complete their separation from one another.

105 It will be appreciated that various changes 110 and modifications may be made in the device as shown in the drawings, and that the same is submitted in an illustrative and not in a limiting sense, the scope of the invention being defined in the following claims.

115 It will be understood that perforations of many different sizes and shapes may be used, and without limiting myself thereto, I have found that perforations of one thirty-second of an inch in diameter or slightly less are 120 amply satisfactory.

120 Removal of the carbon sheets, altogether, may be effected by fingers as shown at F.

I claim:

125 1. A device including an original sheet, a copy sheet, a carbon sheet therebetween, and means for detachably interconnecting said sheets including a fastening means for interconnecting the carbon sheet to the other sheets, and a second fastening means for in-

terconnecting the original and copy sheets independently of the carbon sheet.

2. In a device having an original sheet, a copy sheet, and a carbon sheet interposed therebetween, the combination of means for detachably interconnecting all the sheets, and other means remote therefrom for detachably interconnecting the original and copy sheets alone.

10 3. In a device having an original sheet, a copy sheet, a carbon sheet therebetween, and means spaced from the carbon sheet and detachably interconnecting the original and copy sheets, supplemental means for detachably interconnecting the carbon sheet to the original and copy sheet independently of the first mentioned means.

20 4. A device including an original sheet, a copy sheet, a carbon sheet therebetween, said sheets being all detachably interconnected along one line and the original and copy sheets alone being detachably interconnected along a line spaced from the first line.

25 5. In a device having an original sheet, a copy sheet, and a carbon sheet therebetween, of means for detachably interconnecting said sheets including a fastening between the carbon sheet and certain of the other sheets, and a second fastener for interconnecting the original and copy sheets alone, the second fastener being stronger than the first fastener.

35 6. The combination with a device having an original sheet, a copy sheet, and a carbon sheet therebetween, of a line of registering perforations through the sheets for detachably interconnecting the same, said perforations having burr-like projections extending into holding engagement in other perforations, and a second line of a detachable fastening including an adhesive interconnecting the original and copy sheets alone.

45 7. In a device having an original sheet, a copy sheet, and a carbon sheet therebetween, the combination of a detachable fastening interconnecting the sheets along one edge thereof, and a second means detachably interconnecting the original and copy sheets alone along another edge of the device, the second means being stronger than the first mentioned means.

55 8. In a device having an original sheet, a copy sheet, and a carbon sheet therebetween, the combination of registering perforations through the sheets, the perforations having burr like projections extending into perforations registering therewith for detachably interconnecting the sheets, a cut out in the original and copy sheets, said carbon sheet projecting through said cut out, and a second detachable fastening interconnecting the original and copy sheets alone.

60 9. In a device having an original sheet, a copy sheet, and a carbon sheet therebetween, the combination of a plurality of registering

perforations in the sheets, certain of the perforations having projections extending into registering perforations of another sheet for detachably interconnecting the sheets, the perforated portion of the carbon sheet being 70 free of oleaginous matter, and a second detachable fastening interconnecting the original and copy sheets independently of the carbon sheet.

10. In a device having an original sheet, 75 a copy sheet, and a carbon sheet therebetween, the combination of means for detachably interconnecting certain of the sheets including a detachable fastener at one edge portion of the device, and a second detachable fastener 80 at another edge portion of the device, the second fastener having registering perforations in certain of the sheets, and one of the sheets having projecting edge portions at certain of its perforations, said projecting portions 85 being engaged with the remaining sheets in perforations thereof registering with the first mentioned perforations.

11. In a device having an original sheet, 90 a copy sheet and a carbon sheet therebetween, the combination of a means for detachably interconnecting the original and copy sheets independently of the carbon sheet, and a second means for detachably interconnecting the carbon sheet to certain of the other sheets, 95 the second means including a plurality of spaced detachable interconnecting portions so constructed as to release the carbon sheet on exerting a pull thereon in the plane of the carbon sheet.

In testimony whereof I affix my signature.
MAX HOPP.
